WILLIAM F. FREEMAN, OF GRAND RAPIDS, MICHIGAN, ASSIGNOR TO GRAND RAPIDS SHOW CASE COMPANY, OF GRAND RAPIDS, MICHIGAN, A CORPORATION OF MICHIGAN.

GARMENT-HANGER.

1,160,060.

Specification of Letters Patent.

Patented Nov. 9, 1915.

Application filed March 15, 1913. Serial No. 754,483.

To all whom it may concern:

Be it known that I, WILLIAM F. FREEMAN, a citizen of the United States, and a resident of the city of Grand Rapids, in the 5 county of Kent and State of Michigan, have invented a certain new and Improved Garment-Hanger, of which the following, taken in connection with the accompanying drawing, is a specification.

10 The garment hanger most extensively used to carry coats, cloaks and like garments consists in two arms meeting and joined together at the central portion of the hanger, the arms extending downwardly and forwardly from the meeting point in either direction therefrom, these arms being smoothed and shaped to conform to the collar and shoulders of a coat or cloak as near as may be to the natural shape thereof, that 15 20 25 30 35 40 45

is with the ends of the arms projecting the outer portions of the shoulders of the garment forward and with the collar fitting closely against a collar forming portion made near the center of the hanger. A suspension means is added to the hanger at the meeting point of the arms and is used to suspend the hanger and garment carried thereby on any convenient hook or rod or other support. In the manufacture of such hangers, it is practically necessary to form the arms from separate pieces of material and to join them together by some form of joint such as to leave the surface of the arms on the rear side smooth to afford a proper 40 45 50 55 60 65 70 75 80 85 90 95 100 105 110

surface for the garment to engage against. The suspension hook is attached to the hanger at this joint and is usually inserted through a hole drilled in the hanger at the meeting point of the two arms. The result of such structure is to make the garment hanger weak at the center and liable to break either from the weight of the garment on the hanger, or from rough usage in placing the loaded hangers on a support, or on dropping a hanger and having it strike on the outer end of an arm, and in other ways.

My invention has for its primary object the strengthening of the hanger at this weak portion and reinforcing of it in all directions in which strain is liable to occur, the means used to reinforce it also serving as a means to secure the suspension hook to the hanger and permitting the elimination of the drilling of the hole in the hanger, thus 55 doing away with this source of weakness.

Furthermore the reinforcing means may be shaped to allow the hook used to suspend the hanger to open to either side of the hanger, some buyers of the hangers preferring hooks with their open sides toward the left side and others toward the right side of the hanger. Various other objects and purposes will appear as the description of the embodiments shown in the drawing progresses.

In the drawings, Figure 1 is a front elevation of a hanger embodying my invention. Fig. 2 is a similar view of a modification, a portion only of the hanger being shown. Fig. 3 is an elevation of the hanger looking 70 from the right of Fig. 1. Fig. 4 is a sectional view taken centrally of the hanger shown in Fig. 1. Fig. 5 is a partial rear elevation.

In constructing the hanger, there is provided two arms 6 which have abutting ends 7 meeting and which when secured together form the hanger bow for insertion within a coat or cloak. Each arm 6 at its inner end is formed with a curved outer surface 8 against which the collar of the coat engages, and is cut away at 9 forming a depression to better receive and shape the collar, the arms then extending forward and downwardly as shown to their outer end which are rounded 85 off at 10. A coat placed on the bow formed by the arms joined together will adjust itself to the form by gravity, the outer ends of the arms throwing the shoulders forward and carrying the coat on the form practically the same as it is naturally carried when worn, except as to the front or open portion of the coat which hangs free. The weight of the garment is borne by the arms of the hanger, and by reason of the shape of the 90 95 bow formed by the forwardly and downwardly extending arms, there is a tendency of the arms to part at their meeting point which must be resisted by the joint there formed. Also when the weighted hanger is placed on its support more or less carelessly, an added strain is given to the joint which is liable to rupture. In the same way, dropping of the hanger on one of its outer ends will serve in many instances to break it. The means used to strengthen the hanger at this joint consists of a plate 11 attached to the front side of the hanger by means of screws 12, the plate extending over a portion of both hanger arms, and having an integral 110

flange 13 extending beneath a portion of both arms and against which said arms bear. In this manner the tendency of the arms to break apart at the joint is resisted, both in 5 the forward and downward direction while at the same time, the rear portion of the arms is left entirely unobstructed and smooth so that no interference with the garment placed on the hanger is had. By this 10 construction a hanger is provided as strong as though made of one piece and capable of standing any usage to which it may be subjected.

The suspension hook 14 is centrally attached to the hanger and at the meeting point of the two arms. In the hanger shown it is secured to the hanger by means of the strengthening plate 11, an embossed portion 15 being formed at the central portion 15 of the plate and extending downward for a portion of its height, the lower portion of the hook lying within the groove formed by such embossed portion and between the plate and the hanger. In Fig. 1, 25 a hole is formed at the lower portion of the embossing and the end of the wire from which the hook is formed is bent and passed through said hole in this manner securing the hook from upward displacement. Other 30 means of securing the hook may be used if desired, in Fig. 2 there being shown two embossed extensions 16 to the embossed portion 15, extending at different angles and practically in line with the hanger arms 6, 35 the lower end of the hook being bent to lie in either groove formed by such extensions, and being retained thereby so as to prevent upward movement of the hook. By placing the lower end of the hook in one extension 40 16 of the embossing, the opening of the hook faces one end of the hanger while if placed in the other extension, it will face the other way.

It will be clear from this description that 45 I have provided a garment hanger with forwardly and downwardly extending arms which is strong and durable and will stand as hard usage as though formed of a single piece of material, and one in which the suspension means therefor is firmly and securely attached without in any manner cutting or drilling the hanger portion itself.

And this structure is of few parts all easily and cheaply made so that the cost of manufacture is small.

55

Various changes in detail may be made without departing from the invention. The disclosure made, accordingly, is to be taken as illustrative and diagrammatic of the invention merely, and not in any sense as 60 limiting the invention to any specific structure.

What I claim as new and desire to secure by Letters Patent is:—

1. A garment hanger comprising opposed arms projecting forwardly and downwardly from a central point of suspension thereof, said arms being formed of separate pieces and having ends in engagement at such central point, and a plate fixedly attached to 70 the adjoining ends of the arms on the front face thereof said plate also having an integral angular section extending under the arms, and against which the inner ends of the arms bear on the under side thereof.

75

2. A garment hanger comprising a coat carrying bow, said bow having downwardly and forwardly projecting arms meeting at a central point of the bow, a plate secured substantially at the center of the bow, said plate having embossed portions lying at angles to each other thereby forming grooves between the plate and hanger, and a suspension hook having an angular lower extension adapted to be seated in different 85 grooves to thereby position the hook in different relation to the bow of the hanger.

80

3. A garment hanger comprising a coat carrying bow, a plate secured substantially at the center of the bow, embossed portions 90 formed in the plate and lying at angles to each other thereby forming grooves between the plate and hanger bow, and a suspension hook having an extension adapted to be seated in different grooves to thereby secure 95 the hook in different fixed relations to the hanger.

In testimony whereof, I have hereunto affixed my signature in the presence of two witnesses:

WILLIAM F. FREEMAN.
